UNITED STATES PATENT OFFICE.

EMILY L. MERRILL, OF DORCHESTER, MASSACHUSETTS.

DESIGN FOR A GARMENT-SUPPORTER.

SPECIFICATION forming part of Design No. 34,612, dated June 4, 1901.

Application filed April 16, 1901. Serial No. 56,170. Term of patent 3 $\frac{1}{2}$ years.

To all whom it may concern:

Be it known that I, EMILY L. MERRILL, a citizen of the United States, residing at Dorchester, in the county of Suffolk and State of Massachusetts, have invented and produced a new and original Design for a Garment-Supporter; and I do hereby declare the following to be a full, clear, and exact description of the same, reference being had to the accompanying drawings, forming a part thereof.

This invention relates to a novel and unique design for a garment-supporter for ladies' and misses' skirts and waists, since it is intended to hold down the waist and belt and to prevent sagging of the skirts.

The leading feature of the design is a thin body having upwardly-converged edges and upper concave and lower convex ends and outwardly curved between its edges and having slots adjacent to the convergent edges and parallel therewith and having centrally-disposed hooks at its concave and convex ends curving in opposite directions from the plane of the body, the hook upon the convex side of the body being long and having its edges downwardly convergent or inclined in an inverse direction to the inclined edges of the said body, and the hook upon the concave side of the body being oblong and of rectangular shape.

The design is illustrated in the annexed drawings, in which—

Figures 1 and 2 are elevations of, respectively, the obverse and reverse sides of the design. Fig. 3 is a top plan view. Fig. 4 is a vertical section.

Corresponding and like parts are referred to in the following description and indicated in all the views of the drawings by the same reference characters.

The design consists of a thin body 1, having its opposite edges 2 upwardly convergent and having its upper end 3 concave and its lower end 4 convex, the two ends 3 and 4 being approximately parallel. The body is curved or bowed between its converged edges 2, so that one side is convex, while the opposite side is concave. Slots 4^a are provided in the body adjacent to and parallel with the converged edges 2 and extend to within a short distance of the upper and lower ends 3 and 4. A hook 5 is located centrally of the concave end 3 and extends in front of the convex side of the body and tapers slightly toward its end. A corresponding hook 6, of oblong and rectangular form, is located medially of the concave end 4 and comes in the rear of the concave side of the body. The hook 6 is of a stub form, and its free edge 6^a portion nearly or quite touches the concave side of the body.

Having thus described the invention, what is claimed as new is—

The design for a garment-supporter, substantially as herein shown and described.

In testimony whereof I affix my signature in presence of two witnesses.

EMILY L. MERRILL. [L. S.]
